UNITED STATES PATENT OFFICE.

ORANGE O. OZIAS, OF DAYTON, OHIO.

DESIGN FOR A PLATFORM FOR SCALES.

SPECIFICATION forming part of Design No. 33,824, dated January 1, 1901.

Application filed December 4, 1899. Serial No. 739,199. Term of patent 7 years.

To all whom it may concern:

Be it known that I, ORANGE O. OZIAS, a citizen of the United States of America, residing and having my post-office address in Dayton, 5 in the county of Montgomery and State of Ohio, have invented and produced a certain new and original Design for a Platform for a Scale; and I hereby declare that the following is a clear, full, and exact description thereof, reference being had to the accompanying drawings, in which like numerals refer to like parts.

In the drawings, Figure 1 illustrates a bottom plan view of a platform for a scale embodying my invention and design. Fig. 2 5 illustrates a side elevational view thereof.

The leading or essential feature of my design for a platform for a scale consists of a circular flat plate having one edge thereof 20 straight and projections from one side of said plate, said projections being at the corners of an imaginary rectangle, one side of which is parallel with the straight edge of said plate, some of said projections being of different

lengths and the edges of said platform being 25 beveled inward upon the face unprovided with said projections.

In said drawings, 10 represents the circular flat plate. 11 represents the straight edge of said circular flat plate. 12 represents the projections from one side of said plate 10, said projections being at the corners of an imaginary rectangle, one side of which is parallel with said straight edge 11 of said plate 10, some of said projections 12 being of different 30 35 lengths, the peripherical edges of said plate 10 being beveled, substantially as shown in Fig. 2.

What I claim is—

The design for a platform for a scale, substantially as shown and described. 40

In witness whereof I have hereunto set my hand this 23d day of November, 1899.

ORANGE O. OZIAS.
